CLAIM

The ornamental design for a wood-type golf club head, as shown and described.

DESCRIPTION

FIG. 1 is a perspective view of a first embodiment of the golf club head showing our new design;

FIG. 2 is a front or face view thereof;

FIG. 3 is a rear view thereof;

FIG. 4 is a left view thereof from the toe end;

FIG. 5 is a right view thereof from the heel end;

FIG. 6 is a top view thereof;

FIG. 7 is a bottom view thereof;

FIG. 8 is a second embodiment of the golf club head shown in FIG. 1, it being understood that the remaining views thereof are otherwise the same as already shown; and,

FIG. 9 is a top view of a third embodiment of the golf club head shown in FIG. 1, it being understood that the remaining views thereof are otherwise the same as already shown.
